UNITED STATES PATENT OFFICE.

JOSEPH A. STEINMETZ, OF PHILADELPHIA, PENNSYLVANIA.

MUFFLER.

1,087,468.

Specification of Letters Patent.

Patented Feb. 17, 1914.

Application filed April 12, 1913. Serial No. 760,678.

To all whom it may concern:

Be it known that I, JOSEPH A. STEINMETZ, a citizen of the United States, residing at Philadelphia, in the county of Philadelphia and State of Pennsylvania, have invented 5 certain new and useful Improvements in Mufflers, of which the following is a specification, reference being had therein to the accompanying drawing.

10 The general object of my invention is to provide an unusually compact and efficient muffler especially adapted for internal combustion engines.

15 In the accompanying drawing, A represents a strong cylindrical tube and B a much larger tube inclosing a medial portion of the tube A and concentric therewith, the annular passage between the two being closed at the ends of the larger tube by imperforate 20 walls C, C', through which the smaller tube projects. The inner tube has near these walls, respectively, sets D, D' of perforations, and between the sets it is closed by a diaphragm E.

25 The end wall C, shown in this instance as integral with the larger tube, is held between nuts F, F' on a threaded portion of the inner tube, and the wall C', which is part of a closely fitting cap passed over the 30 corresponding end of the tube B, is similarly held by nuts F², F³, the latter nut, however, being a cup having lateral slots F⁴. The annular space between the tubes contains a series of

35 oppositely turned rounded cups G, G' which have their bottoms so perforated that they fit and slide upon the inner tube, while all taken together, abutting against each other, fill the space between the walls C, C'. Each 40 cup is provided with a set of perforations H, preferably at some distance from the wall of either tube, and all are held firmly, and even put under spring tension when desired, by the suitably adjusted nuts holding the end plates C, C'.

The parts being assembled as shown and gases under very high tension being admitted at the right hand end of the inner tube, there will be a practically noiseless discharge of the gases at the opposite end of the structure, for the heat energy is partly converted into work and partly radiated, and the velocity is very greatly reduced. The entering gases pass laterally from the 50 inner tube into the first cup, which allows expansion through its greater volume and

which is pressed to the left, springing all the other cups slightly. Having here lost some heat by radiation, expansion and work, the gas passes through the series of small 60 perforations into the annular chamber between the first and second cups, a chamber having very great radiating surface in comparison with its capacity. Thence it passes into the approximately spherical chamber 65 between the next two cups, then into another chamber or triangular cross section, like that between the first and second cups, and then, if there be but the four cups shown for illustration, into a terminal cup, whence it passes 70 again into the inner tube and is discharged through the slots F⁴.

As the main parts of the apparatus are of thin spring metal, it is light, radiates rapidly, and the cups spring under great stress, 75 and instantly return to normal form when stress ceases.

It is important that all the parts may be readily separated for cleaning or repair, and that the gas always travels in the same general direction and no part of the stream is 80 jacketed by a returning stream.

It has been found that satisfactory results can be obtained without undue length of the apparatus, and that loss in radiation practically neutralizes the gain which might be sought by returning the gases and thus lengthening their path without correspondingly lengthening the device.

What I claim is:

1. In a muffler, the combination with a terminally closed tube, of a second smaller concentric tube passing axially through the first, having, within and near the ends of the first sets of lateral perforations, a 95 partition fully obstructing the tube between said sets, and a series of oppositely turned, laterally perforated resilient rounded cups loosely mounted on the inner tube and fitting both tubes, one terminal cup being in 100 position to receive gases from the perforations of the first of said sets and the other in position to discharge through the second set.

2. In a muffler, the combination with a 105 tube closed at one end and having at the opposite end an adjustable cap closure, of a smaller concentric tube passing axially through the first tube, and having within the same near its ends sets of lateral perforations, a stop cutting off the passage 110 through the tube between said sets, a linear

series of similar, oppositely turned, approximately hemispherical resilient perforated cups threaded loosely upon the inner tube and fitting both tubes, and means for 5 adjusting said cap to vary the pressure upon the cups.

3. In a muffler, the combination with a tube provided with a set of lateral perforations near each end and with a stop fully 10 obstructing its interior between said sets, of a larger tube with the same axis and having end closures carried inward and fixed to the smaller tube between its ends and said sets respectively, and a series of slidable oppositely turned cups pressed toward each 15 other longitudinally of the tubes, fitting both tubes and provided, respectively, with sets of perforations between their lines of contact with the two tubes.

4. The combination with a tube provided with an imperforate central diaphragm and with sets of lateral perforations near its open ends, of a series of oppositely turned rounded, laterally perforated cups each fitting and sliding upon said tube, the interiors of the terminal cups being in communication with said sets, respectively, a second concentric tube fitting the margins of the cups and terminally closed against the 25 exterior of the inner tube.

5. A muffler receiving gases at one end and discharging them at the opposite end and comprising a tube closed at one end and with a series of oppositely turned, approximately hemispherical resilient diaphragms, each having in its curved surface a set of perforations, a smaller concentric tube passing axially through the first tube and the 30 cups, and a loose cap closing the remaining

end of the outer tube, and an adjustable nut 40 working on the projecting open end portion of the smaller tube for pressing said cap against the series of cups.

6. The combination with concentric tubes provided with a slidable perforated dia- 45 phragm in the intervening annular space between them, of means for discharging into one end of said space hot gases under high tension, and discharging the same gases from the opposite end, and a yielding 50 element resisting the sliding of said dia-phragm under the pressure of gas upon it.

7. The combination with concentric tubes having the annular intervening space terminally closed, of a series of two cup-like 55 oppositely turned perforated diaphragms slidably fitting said space, means for delivering hot gases into one end and discharging them from the other end of said space, and a spring opposing the sliding of one 60 diaphragm under pressure of gas upon it.

8. The combination of a muffler casing of thin metal provided with inlet and discharge passages, of internal diaphragms adapted to divide the interior into communicating chambers and to resist strongly 65 yet yieldingly movements urged by momentary increases of gas pressure; whereby the muffler radiates a portion of the heat of the entering gas and simultaneously converts 70 another portion into work, insuring a rapid decrease in temperature and tension.

In testimony whereof I affix my signature in presence of two witnesses.

JOSEPH A. STEINMETZ.
